UNITED STATES PATENT OFFICE

2,474,353

ARMATURE WINDING MACHINE

William A. Goodman, Atlanta, Ga.

Application January 23, 1946, Serial No. 642,919

1 Claim. (Cl. 242—13)

1

The present invention relates to new and useful improvements in armature winding machines and has for its primary object to provide a device of this character in which the coils of the armature may be quickly and easily wound.

An important object of the present invention is to provide a device of this character embodying means for guiding the wire into the slots of the armature core as the armature is being wound and without necessitating the removal of the commutator from the armature.

A still further object is to provide a machine of this character of simple and practical construction, which is efficient and reliable in operation, relatively inexpensive to manufacture and otherwise well adapted for the purpose for which the same is intended.

Other objects and advantages reside in the details of construction and operation as more fully hereinafter described and claimed, reference being had to the accompanying drawings forming part hereof, wherein like reference numerals refer to like parts throughout, and in which:

Figure 1 is a side elevational view,

Figure 2 is a top plan view,

Figure 3 is a fragmentary sectional view taken substantially on a line 3—3 of Figure 1,

Figure 4 is an enlarged and elevational view of the chuck body showing the wire guides or wings attached thereto, and

Figure 5 is a side elevational view thereof with parts broken away and shown in section.

Referring now to the drawings in detail, wherein, for the purpose of illustration, I have disclosed a preferred embodiment of the invention, the numeral 5 designates a drive shaft journaled in bearings 6 supported on a suitable base or stand 7 on a work bench 8, the rear end of the shaft having a bevel gear 9 secured thereto driven by a similar gear 10 from a suitable source of power.

To the front end of the shaft 5 is secured a chuck body 11 formed with a channel 12 in its front face to receive one side of the core 13 of an armature, the channel 12 of the chuck body having a longitudinally extending slot 14 therein for receiving a key 15 adapted to enter one of the slots 16 of the armature core to secure the armature in a fixed position therein and against rotation or turning movement in the channel.

To each longitudinal side edge of the channel 12 at the front face of the chuck body 11 is secured a wire guide or wing 17 having its ends curved rearwardly, as indicated at 18. The outer

5 side edges of the wings or wire guides are also curved rearwardly, as indicated at 19, and one end of the wings or guides is formed with an inwardly projecting extension 20 with the extensions of the respective wings terminating in spaced relation with respect to each other to form an opening 21 therebetween in alignment with the key 15 to provide access thereto for removal of the key from the slot 14 when locking the armature in an adjusted position.

10 The inner edges of the wings or wire guides 17 terminate adjacent a pair of the slots 16, as shown in Figure 3 of the drawing, whereby to guide the wire 22 in the slot of the armature core in the usual manner well known in the art.

15 As shown more clearly in Figure 1 of the drawing, the curved ends 18 of the wire guides or wings 17 are spaced from the commutator 23 of the armature whereby the wire may be fed to the slots of the armature core without interference by the commutator and without necessitating a removal of the commutator from the armature.

20 The opposite side of the armature core 13 is engaged by a tail stock clamp 24 for retaining the armature core in the channel 12, the clamp 24 also being formed with a channel 25 conforming to the curvature of the armature and is secured at one end of a shaft 26 journaled in 25 a pair of intermediate and end bearings for said shaft designated 27, 27', respectively, and supported on a base 28 above the bench 8.

25 The clamp 24 is yieldably held in position by means of a coil spring 29 having one end bearing against the end bearing 27' and with its other end bearing against a collar 30 secured to the shaft.

30 It is believed the details of construction, manner of operation and advantages of the device 35 will be readily understood from the foregoing, it being apparent that the armature core 13 is clamped in position between the chuck body 11 and the tail stock clamp 24, and upon rotation of the shaft 5 the armature core will be turned 40 so that the wire 22 will be guided in the slots 16 by the wire guides or wings 17.

45 In view of the foregoing description taken in conjunction with the accompanying drawings, it is believed that a clear understanding of the construction, operation and advantages of the device will be quite apparent to those skilled in this art. A more detailed description is accordingly deemed unnecessary.

50 It is to be understood, however, that even though I have herein shown and described a

preferred embodiment of my invention that the same is susceptible to certain changes fully comprehended by the spirit of the invention as herein described and the scope of the appended claim.

Having thus described the invention, what I claim is:

An armature winding machine comprising a chuck body shaped to receive one side of an armature core, a key removably carried by the chuck body for engaging the core to secure the latter against rotation in the body, means for rotating the chuck body, a releasable rotating clamp engaging an opposite side of the core, said core including a commutator at one end, and a pair of wire guides attached to the chuck body at opposite sides of the core, said guides comprising plates having rearwardly curved outer side and end portions adapted to feed the wire into the slots of the armature between the core and commutator, said plates at one end having lateral extensions turned toward each other and

spaced apart to provide an opening therebetween in alignment with said key for removal of said key therethrough.

WILLIAM A. GOODMAN.
